CLAMP ATTACHMENT FOR FUSE
ANCHORING CLIPSJames B. Cooper, Clarkdale, Ga., assignor of
thirty per cent to Gabriel J. Asensio, Clark-
dale, Ga.

Application August 1, 1938, Serial No. 222,568

3 Claims. (Cl. 200—134)

This invention relates to a novel clamp attachment for use in connection with a conventional U-shaped clip such as is used on a mounting block for a safety fuse, and the main purpose of the invention is to serve to firmly bind or clinch the terminals of the fuse between the customary spaced parallel resilient retention jaws of said fuse clip.

Needless to say, I am aware of the fact that supplementary fastening and clamping accessories of this general type have been provided to accomplish somewhat the same purpose. Under the circumstances, it is evident that my primary aim is to generally improve upon appliances and appurtenances of this special line of endeavor by providing a structurally distinct and appreciably different means in the nature of a two-part attachment susceptible of being expeditiously applied to the regulation or standard fuse clip without requiring alteration in the clip construction.

Briefly described, the improved attachment or clamp comprises a special adapter unit for separable connection with the base portion of the clip, and a complementary hingedly mounted resilient clasp unit expressly designed for clamping coaction with the usual terminal anchoring jaws or flanges on said clip.

More specifically, the preferred embodiment of the invention comprehends the adoption and use of means which is applicable to the base portion of the clip to serve as a support and hinging means for the clamping unit, said latter unit being in the form of a lever or especially shaped arm carrying a pair of duplicate grips to embrace the jaws of the clip and to press the jaws firmly against the terminal end of the fuse in such a manner as to guard against accidental displacement of the fuse from the clip.

Other features and advantages will become more readily apparent from the following description and drawings.

In the drawings:

Figure 1 is an elevational view showing a fragmentary portion of a mounting base, a conventional fuse clip thereon, a portion of the fuse connected with the clip, and further illustrating the attaching clamp fastened on the clip.

Figure 2 is a horizontal sectional view taken on the plane of the line 2—2 of Figure 1, looking downwardly in the direction of the arrows.

Figure 3 is an end view of Figure 1 observing it in a direction from right to left.

Figure 4 is a transverse or vertical sectional view taken approximately on the plane of the line 4—4 of Figure 1.

Figure 5 is a perspective illustration of the swingable or hingedly mounted lever unit provided with the clamping means.

Figure 6 is a substantially central longitudinally cut sectional view taken on the plane of the line 6—6 of Figure 3.

Figure 7 is a top plan view of the special adapter member which constitutes the attaching means for the lever or clamping unit.

Figure 8 is a fragmentary perspective illustration of one end portion of the adapter unit showing the parts bent into their relative retention positions.

Referring now to the drawings by distinguishing numerals, it will be observed that the standard mounting block is denoted by the numeral 9 and that the conventional terminal or anchoring clip 10 is suitably fastened thereto. The clip 10 comprises the customary substantially triangular attaching base 11 having upstanding spaced parallel flanges 12 whose upper ends flare outwardly and serve as jaws between which the terminals 13 of the fuse 14 are located and held. These are conventional parts and it is obvious that the jaws 12 frequently lose their tenacious ability to securely hold the end of the fuse therebetween. Under the circumstances, it has been found that supplementary retention and clamping means is frequently advisable to guard against accidental displacement. This is particularly so when the clips are inverted from a ceiling or the like and are prone to allow the fuse to drop out as is caused by vibration and other evident forces.

In accordance with my idea, the clamping unit indicated by the numeral 15 in Figure 5 forms a practicable and feasible means cooperating with the jaws 12 to firmly retain the terminal 13 therebetween. The unit 15 is preferably constructed from a single sheet of metal of appropriate character and includes a part 16 which may be unitarily referred to as a lever. This lever, however, may be said to include the depending portion 17 of an L-shaped actuating member 18. This member 18 terminates in an eye 19 which is adapted to accommodate a hook on the end of an insulation stick (not shown) which is employed as an implement or tool for swinging the unit 15 toward and from clamping position. The lower end portion 20 of the lever may be designated as a shank and terminates at its bottom in a hinge knuckle 21. The central portion of the lever or arm, denoted by the numeral 22, may be described as the web portion of a U-shaped clamp since the clamping arms 23 are bent at right

angles from this. These arms are longitudinally bowed so that their free ends 24 flare outwardly to facilitate engagement with the jaws 12 when the clamp is swung upwardly from its open position (not shown) to its closed binding or clamping position illustrated in the drawings.

Another way of visualizing the construction of the unit 15 is to merely refer to it as a U-shaped clamp which embraces the jaws 12 which clamp 10 is provided with a hinging tang or shank 20 and an L-shaped part 16 to function as a convenient tool or implement accommodating element to expedite operation of said unit 15. Broadly, however, said unit 15 is merely in the nature of a hinged lever or arm provided with clamping fingers 23.

The hinging and attaching unit for the clamp unit 15 is denoted by the numeral 25 and is better shown in detail in Figures 7 and 8. This comprises a substantially V-shaped plate 26 which is fashioned and proportioned to slip into the correspondingly shaped upper portion of the base 11 as illustrated in Figure 4. At opposite ends the plate is provided with bendable extensions, there being two pairs of said extensions 27 at one end and relatively short extensions 28 at the opposite end. These are merely bent upon themselves to define hooks which engage over the end portions of the base 11 to obviate the necessity of using special bolts or similar fastenings. At the right hand end, the plate is provided with a pair of supplementary extensions 29 whose inner or free ends are bent as indicated at 30 to function as ears which ears serve to accommodate a pintle pin 31 which serves as a hinge pin for the knuckle 21. Thus, in a sense, we have an adapter which is in the form of a plate slipped into the base 11 and attached thereto by bendable hooks, said adapter 40 being provided at one end with ears or equivalent elements 30 to accommodate a hinge pin on which the knuckle 21 is pivotally mounted. This provides a simple and economical way of hingedly connecting the clamping unit 20 to the base 11. 45 It is submitted that a two-part attachment of the type herein illustrated and described constitutes a satisfactory and reliable clamp to embrace the jaws 12 and to cooperate therewith in holding the fuse-end 13 securely in place. 50 It is thought that persons skilled in the art

to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice, if desired.

What is claimed is:

1. A fuse anchoring and clamping assembly of the class described comprising a clip unit adapted to be secured to a relatively fixed base and including a U-shaped member defining a pair of parallel duplicate resilient jaw forming 15 flanges, an adapter unit mounted in the basal portion of the clip unit, one end of the adapter unit projecting beyond the corresponding end of the clip unit and said projecting end being provided with a hinge pin, a vertical arm hingedly 20 attached to said pin and swingable toward and from the adjacent end portion of the clip unit, said arm rising to a point above the upper edges of the flanges and having a laterally directed portion overlying said flanges and terminating in 25 an eye to accommodate a tool, said arm being provided with a pair of parallel resilient clamping fingers fashioned to cooperate with the jaw flanges of said clip unit.

2. As a new article of manufacture, and as a 30 component part of an assemblage of the class described, a substantially V-shaped adapter plate adapted to serve as an insert and to fit removably in the basal portion of a conventional channel-shaped terminal accommodation clamping 35 clip, said adapter plate having attaching hooks at opposite ends and being provided at one end with a lever accommodation hinge pintle.

3. An attachment of the class described comprising a substantially V-shaped adapter plate provided at opposite ends with attaching hooks, and provided at one end with a hinge pintle, a clamping lever unit including a lever having a knuckle hingedly connected with said hinge pintle, and including a pair of resilient clamping 45 fingers fashioned to cooperate with the conventional clamping jaws of a fuse clip of the class described.

JAMES B. COOPER.
